WRENCH HAVING PIVOTAL JAW COOPERABLE WITH MULTISURFACED FIXED JAW

Herman Bachli and Harry S. Shapiro, Chicago, Ill., assignors to Chicago Specialty Manufacturing Co., Chicago, Ill.

Application September 7, 1950, Serial No. 183,564

6 Claims. (Cl. 81—98)

1

Our invention relates to improvements in wrenches, the general object of the invention being the provision of a wrench having plural sets of teeth on a fixed inner jaw and having a multi-axis-pivoted outer jaw, whereby a wrench operation may be effected by lateral movement of the handle or by rotational movement about the axis of the handle, thereby permitting the wrench to be used in the usual manner or in closely confined or restricted places where use of a conventional wrench would be prevented.

Another object of our invention is the provision of a wrench of the foregoing type in which one jaw is movable about an axis transverse to the axis of the handle so that it can be moved to different positions and be yieldingly retained in any one position of adjustment to facilitate engagement of the jaws of the wrench with a work piece.

A further object of our invention is the provision of a wrench which is simple in construction, durable in service and economical to manufacture.

Other and further objects and advantages of our invention will become apparent from the following description when considered in connection with the accompanying drawings in which:

Fig. 1 is a perspective view of a preferred embodiment of our invention showing the movable jaw in one position of operation.

Fig. 2 is a fragmentary elevational view of the wrench showing the movable jaw in another position of operation, and

Fig. 3 is a cross-sectional view taken substantially on line 3—3 of Fig. 1.

Referring to the drawings, the numeral 5 indicates a tubular handle, the lower end of which is preferably perforated to receive a rod member 6 which is adapted to be engaged as by a hand to rotate the handle 5 about its longitudinal axis. A wrench jaw element 7 including a head 8 and a shank 9 is disposed at the upper end of the handle 5 with the shank being received within the bore of the handle 5. The shank 9 is fitted into the bore of the handle 5 so as to be secured therein against relative movement. The head 8 is cylindrical in form and has formed on its cylindrical surface a series of hardened serrations or teeth 10 extending parallel to the axis of the handle. The top surface of element 7 may either be flat or arcuately formed and is also provided with a series of serrations or teeth 11 which extend perpendicularly to the axis of the handle.

The head 8 is provided with a transverse bore 12 in which is received the stud 15 of a swivel member, generally indicated by the numeral 13, the swivel member being secured against removal

2

from the head 8 by an annular ring 14 received in an annular groove 16 at the end of stud 15, the ring 14 providing a shoulder adapted to abut against a shoulder 17 provided in the bore 12. A coil spring 18 received within the bore 12 abuts the shoulder 17 and a shoulder 13a provided on the member 13 and serves to frictionally retain the member 13 in a position of adjustment. The member 13 is provided with an ear 19 which is perforated to receive a pin 21 on which is pivotally supported a jaw member 22. The said jaw member is substantially arcuate in form and is provided on its surface with a series of hardened serrations or teeth 23 arranged parallel to the axis of the pin 21. Integrally formed with the jaw member 22 are spaced perforated ears 24 in the perforations of which is received a pin 21, said pin being peened at its ends to permanently secure the jaw member 22 to the swivel member 13.

As will be apparent, the swivel member 13 permits the jaw member 22 to be rotated at least through an angle of 180° so that the jaw member 22 may be made to cooperate with opposite serrations or teeth 10 on the head 8, or with the serrations 11 on the arcuate surface of the head 8. Thus, as viewed in Fig. 1, the jaw member 22 has been swung so that the serrations 23 thereof are in parallel relationship with the serrations 10 on the head 8, the jaw member 22 being in a position relative to the head 8 such that the gripping action on a work piece as a circular rod or pipe 26, indicated by the broken lines, will be increased as the wrench handle 5 is turned in a clockwise direction, thereby to tighten up an object having a conventional right-hand thread. The jaw 22 may also be rotated 180° to position said jaw to cooperate with the serrations 10 on the opposite side of the head 8, thereby requiring that the handle 5 be rotated in a counterclockwise direction to increase the grip of the wrench on the object to be turned.

With the jaw 22 in either of the positions above described, the wrench may be used in closely confined or restricted places, and may be rotated about the axis of the handle upon the application of a torsional force on the handle 5.

The jaw 22 may be positioned as illustrated in Fig. 2, so that the serrations or teeth 23 are in parallel relation to the teeth on the head 8. In this position the work piece is gripped between the teeth 23 and 11 of the jaw 22 and head 8 respectively. With the jaw 22 in this position, the wrench may be used in the same manner as a conventional wrench, the handle 5, in this instance, serving as a lever to which a pulling or

pushing force may be applied to move the handle in the direction of the arrow to the position indicated by the broken lines.

It will be apparent that the pressure of spring 18 against shoulder 13a provides the necessary friction to retain the jaw 22 in a position of adjustment, but yet to permit rotation of the said jaw about the axis of stud 15, so that it may be placed in position for use.

We claim:

1. A wrench comprising a handle, a head fixed at one end of said handle, said head being substantially cylindrical in form and having teeth on the cylindrical surface extending parallel to the axis of said handle, said head having an end face and teeth on said face extending transversely of the axis of said handle, said head having an opening therein extending at a right angle to said last mentioned teeth, a swivel member extending into said opening and rotatable therein, means to frictionally retain said swivel member against free rotation, and an arcuate jaw member having one end pivotally attached to said swivel member so as to be movable about an axis perpendicular to the axis of rotation of said swivel member.

2. A wrench comprising a handle, a head fixed at one end of said handle, said head being substantially cylindrical in form and having teeth on the cylindrical surface extending parallel to the axis of said handle, said head having an end face and teeth on said face extending transversely of the axis of said handle, said head having an opening therein extending at a right angle to said last mentioned teeth, a swivel member having a stud portion received in said opening and rotatable therein, a coil spring received within said opening and in concentric relation to said stud portion, said spring bearing against a shoulder on said stud portion to frictionally retain the same against free rotation, and an arcuate jaw member having one end pivotally attached to said swivel member so as to be movable about an axis perpendicular to the axis of rotation of said swivel member.

3. A wrench comprising a handle, a head fixed at one end of said handle, said head having teeth extending parallel to the axis of the handle and other teeth extending transversely of the axis of said handle, said head having an opening therein extending at a right angle to said last mentioned teeth, a swivel member extending into said opening and rotatable therein, means to frictionally retain said swivel member against free rotation, and an arcuate jaw member having one end pivotally attached to said swivel member so as to be movable about an axis perpendicular to the axis of said swivel member.

4. A wrench comprising a handle, a head fixed at one end of said handle, said head having teeth extending parallel to the axis of the handle and other teeth extending transversely of the axis of

said handle, said head having an opening therein extending at a right angle to said last mentioned teeth, a swivel member having a stud portion received in said opening and rotatable therein, a coil spring received within said opening and in concentric relation to said stud portion, said spring bearing against a shoulder on said stud portion to frictionally retain the same against free rotation, and an arcuate jaw member having one end pivotally attached to said swivel member so as to be movable about an axis perpendicular to the axis of rotation of said swivel member.

5. A wrench comprising a tubular handle, a head having a shank received in one end of said handle and fixed thereto, said head being substantially cylindrical in form and having teeth on the cylindrical surface extending parallel to the axis of said handle, said head having an end arcuate face and teeth on said face extending transversely of the axis of said handle, said head having an opening therein extending at a right angle to said last mentioned teeth, a swivel member extending into said opening and rotatable therein, spring means bearing against said swivel member to frictionally retain the same against free rotation, and an arcuate jaw member having one end pivotally attached to said swivel member so as to be movable about an axis perpendicular to the axis of rotation of said swivel member.

6. A wrench comprising a tubular handle, a head having a shank received in one end of said handle and fixed thereto, said head having teeth extending parallel to the axis of said handle and other teeth extending transversely of the axis of said handle, said head having an opening therein extending at a right angle to said last mentioned teeth, a swivel member having a stud portion received in said opening and rotatable therein, a coil spring received within said opening and in concentric relation to said stud portion, said spring bearing against a shoulder on said stud portion to frictionally retain the same against free rotation, and an arcuate jaw member having one end pivotally attached to said swivel member so as to be movable about an axis perpendicular to the axis of rotation of said swivel member.
